UNITED STATES PATENT OFFICE.

BENJAMIN JUDD ABBOTT, OF CHICAGO, ILLINOIS, ASSIGNOR TO CHARLES H. DURPHY, OF SAME PLACE.

ENGRAVING-MACHINE.

SPECIFICATION forming part of Letters Patent No. 593,556, dated November 16, 1897.

Application filed March 29, 1897. Serial No. 629,645. (No model.)

To all whom it may concern:

Be it known that I, BENJAMIN JUDD ABBOTT, a citizen of the United States, residing in Chicago, in the county of Cook and State of Illinois, have invented a new and useful Improvement in Die-Sinking Machines, of which the following is a specification.

The machine which constitutes the subject-matter of this invention is one which is more especially designed for doing the die-sinking work in machines employing dies in considerable numbers of two kinds—viz., roller-dies, in which the matrices are formed upon the periphery of cylindrical rolls, and also flat dies, in which the matrices are formed in flat blocks, the roller-dies being used in such machines for rolling the shanks of articles and the flat dies for shaping the heads or other parts. Although thus designed for doing a special kind of work, the machine is one adapted to perform any kind of die-sinking, either upon a cylindrical or upon a plane surface, and also do almost every variety of milling-work.

25 The nature of the invention will fully appear from the following description and claims, taken in connection with the accompanying drawings, which form a part of this specification, and in which—

30 Figure 1 is a front elevation of the improved machine. Fig. 2 is a side elevation; Fig. 3, a vertical section from front to rear; Fig. 4, a sectional plan, and Figs. 5, 6, 7, 8, 9, 10, 11, and 12 detail views.

35 In the drawings similar letters of reference indicate like parts throughout the several figures.

The organization of the machine is such that the mechanism which carries and rotates 40 the milling-tool limits its penetration and governs and controls the extent of movement of the chuck or work-holder, whether the latter be the one designed for holding flat or cylindrical dies is the same, and thus in a single 45 machine is combined mechanism for sinking either flat or cylindrical dies at pleasure, and for convenience of description the machine as a whole will first be described with relation to its operation as a machine for sinking 50 dies upon a cylindrical surface—i. e., roller-dies.

The roller or cylinder upon the surface of which are the dies to be sunk is represented at A, mounted on the projecting end of the shaft B, which shaft may be termed the "work-holder" shaft. This work-holder shaft, by means of mechanism presently to be indicated, is oscillated through any required arc by the operation of the machine, the extent of the oscillation being determined by adjustment, so that the shaft B will be swung through any determined arc, first in one direction and then in the other, to an extent according to the length of cut required in sinking the die on the face of the roller which is being operated upon, and said shaft or work-holder B is so mounted in its bearings and connected to its driving mechanism that it may also move endwise or be moved endwise to accommodate the lateral operation of the milling-tool or cutter.

The endwise movement of the shaft or work-holder B is accomplished as follows: Mounted on the shaft B and oscillating therewith is a finger or fingers B', and mounted 75 on the non-revolving bearing B² is a pattern B³, the face of which where the finger B' comes in contact with it is given a cam shape or configuration corresponding to the lateral outline of the matrix which is to be cut in the 80 surface of the oscillating work. A spring B⁴, bearing at one end against the box B² and at the other end against a collar B⁵ and connected to the shaft B by a removable pin B⁶, exerts a constant tendency to thrust the shaft B inward and to hold the finger B' in contact with the pattern B³, so that as the shaft B oscillates, carrying the finger B' over the pattern, the configuration on the surface of the latter, together with the said spring, causes the shaft 85 B to carry the work in and out under the milling-tool, whereby the latter is caused to cut the required outline laterally, as will be readily understood.

For adjusting the position of the work, in 90 and out without interfering with the operation of the foregoing mechanism, a rack B⁷, fixed to the box B², into which the rack-pinion B⁸, carried on the shaft B⁹, mounted in the framework of the machine and having the 95 hand-wheel B¹⁰, is provided. By rotating the hand-wheel B¹⁰ the shaft B and its boxing

B² and the parts connected therewith may be moved bodily out or in as the work may require, and this without interfering with the operation of the pattern or guide B³.

5 The mechanism for imparting to the shaft B a predetermined reciprocating oscillation is as follows: C is a sleeve splined to the shaft B. Keyed to the sleeve C is the plate or spur-gear C', having a groove C² on its side.

10 Mounted in the groove C² are two stop arms or lugs C³ C⁸, held in the groove by clamping-bolts C⁴, so that they may be adjusted to any required position in the groove. For further nicety of adjustment the stop-arms are provided with contact-screws C⁵, tapped into said arms, so that said contact-points may be extended or withdrawn for minute adjustment by simply turning them. Standing in the path of these contact-arms is the arm C⁶, connected to the rock-shaft C⁷, mounted on the frame of the machine and carrying at its other end the arm C⁸. The latter is connected by the bar C⁹ to the lever C¹⁰, fulcrumed in the frame of the machine and carrying at its other end the rod C¹¹, said rod C¹¹ being connected to a reversing-clutch which reverses the movement of the gearing that drives said plate C' and consequently reverses the movement of said shaft B. The friction-clutch is shown at C¹² and is mounted to slide upon and rotate with the power-shaft C¹³. Mounted loosely on this same shaft C¹³ are the opposing bevel-pinions C¹⁴ C¹⁵, meshing with the bevel-gear C¹⁶, keyed to the vertical shaft C¹⁷.

15 When the clutch C¹² is moved in one direction, it engages the pinion C¹⁴ and causes the shaft C¹⁷ to rotate with a corresponding rotation, and when said clutch is moved in the other direction it connects the pinion C¹⁵ to the driving-shaft and causes the rotation of the shaft C¹⁷ to be reversed. At the lower end of the vertical shaft C¹⁷ is a worm C¹⁸, meshing into a screw-gear C¹⁹, carried on the shaft C²⁰. Mounted on this shaft C²⁰ are a set of graded gears C²¹, any one of which may be connected to said shaft by means usually employed in such cases, as will be understood by reference to Fig. 4, while the others will remain loose. On the sleeve C and connected to the plate C' are corresponding graded gears C²². By this arrangement the relative speed of the rotation of the shaft B may be changed as required by the work being done, and it will now be seen that by means of the gearing and mechanism above described power applied to the driving-shaft C¹³ to cause the same to rotate in one direction will be transmitted through said gears and mechanism and converted into a predetermined oscillation through a stated and adjustable arc and with a stated and adjustable speed at the work-holder or shaft B.

20 The cutting or milling tool and its relations and movements will now be described. The milling-tool itself is shown at D and may be of any of the ordinary forms of milling-tools or cutters. It is secured to the end of the

rotating spindle D', mounted in the sliding head D², which head in turn is fitted to slide upon the adjustable carriage D³, the latter being provided with a rack D⁴, which is engaged by a pinion D⁵ for the purpose of feeding the milling-tool down by the means presently to be described to adjust it to a cutting position. Between the sliding head D² and the adjustable carriage D³ is placed a spring D⁶, which, added to the gravity of said sliding head, tends to keep the milling-tool pressed down to its work. The shaft D' is splined to a pinion D⁷, which meshes with a pinion D⁸, carried on the driving-shaft C¹³, so that the milling-tool D is made to revolve rapidly and at the same time is free to move up and down. On the sliding head D² is mounted a finger D⁹ for feeding a pattern D¹⁰, which pattern is mounted on the shaft B. This pattern D¹⁰ is for guiding the milling-tool in a vertical direction and is given a configuration corresponding to the varying depth to which the die is to be sunk. It will thus be seen that a pattern is provided in two planes at right angles to each other, the pattern D¹⁰ guiding the milling-tool in the vertical plane and the pattern B³ guiding the work in the horizontal plane.

25 As it seldom happens that a matrix to be cut is shallow enough to be sunk by a single traverse of the milling-tool, it is necessary or desirable that means shall be provided for feeding the milling-tool downward a distance equal to what it can easily cut at each traverse. This feed is provided for by the rack D⁴ and pinion D⁵. To the shaft of the pinion D⁵ is fixed a hand-wheel D¹¹, which is splined thereto and affords a means for turning the feed by hand when occasion requires—as, for example, when it is desired to lift the milling-tool bodily away from the work. In order that this feed shall be also capable of being or becoming automatic, I provide the shaft D¹², on which the pinion D⁵ is carried, with a bevel-gear D¹³, which is mounted loose on the shaft, but which can be clamped thereto by a friction-clutch D¹⁴, carried on the hand-wheel D¹¹, the clamping being effected when required by tightening up the hand-bolt D¹⁵ on the screw D¹⁶. By this arrangement the bevel-gear D¹³ may be made tight or loose on the shaft at pleasure, according as the hand-feed or the automatic feed be used.

30 The feed-motion, when automatic, is imparted to the bevel-gear D¹³ as follows: A short shaft carries at one end a bevel-pinion D¹⁷, which meshes with the gear D¹³, and at the other end a bevel-pinion D¹⁸, meshing at opposite sides with two loose bevel-pinions D¹⁹ D²⁰, each of which pinions carries a ratchet D²¹, arranged for working in opposite directions by pawls D²² D²³, said pawls being carried by the rock-shaft D²⁴. The end of this rock-shaft is provided with an arm D²⁵, which engages a fork D²⁶, carried on the end of the sliding rod D²⁷, the other end of which rod is connected adjustably to the lower end of the

lever C¹⁰, above described, and which is the lever that operates to reverse the gearing that drives the shaft B.

It will be seen, if the above explanation has been followed, that at each movement of the lever C¹⁰, and consequently at each reverse of the movement of the work-holder or shaft B, the rod D²⁷ is moved in one direction or another, causing the shaft D²⁴ to rock in the same direction, and this motion of the rock-shaft is transmitted by means of one or the other of the two ratchets into a rotary movement of the pinions D¹⁷ and D¹⁸ and the gear D¹³ and the shaft to which it is connected and which carries the pinion D⁵, so that the movement of the pinion D⁵ will be a rotary movement of an intermittent character, always in the same direction, to feed the head carrying the milling-tool downward a stated distance, and occurring at the beginning of each traverse of the tool on the work. In order that the amount of this feed may be regulated and adjusted to be greater or less, the connection between the rod D²⁷ and the lever C¹⁰ is a slotted one, and an adjusting-screw D²⁸ is provided for adjusting the amount of lost motion permitted, the length of the stroke of the rod D²⁷ being inversely as the amount of lost motion permitted.

By the foregoing mechanism it will be seen that when the automatic feed is applied the milling-tool will be fed down a stated and predetermined distance at the beginning of each traverse of the tool in the work and that the amount of this downward feed is capable of exact regulation to suit the requirements of the work.

To avoid the necessity of constant watching and repeated measurement and to provide against accidentally sinking a matrix too deep, an automatically-operating feed-stop is applied to the tool-feed as follows: Connected to the tool-carrying head is a vertical rod E, working in a slide E' and marked with distance-marks E², which may for convenience be, say, one-eighth of an inch apart for purposes of rough adjustment. This rod E carries adjustably secured to it an arm E³, bearing an adjustable contact-finger E⁴ for minor adjustment. This contact-finger E⁴ is in position to strike against the short end of the lever E⁵, the long arm of which is connected by a rod E⁶ to the rod D²⁷, which actuates the feed, so that when the tool-carrying head shall have descended far enough to bring the contact-finger E⁴ into contact with the lever E⁵ the rod D²⁷ will thereby be lifted so that its fork D²⁶ is disengaged from the feed-operating rock-shaft D²¹ and the further downward feed of the tool thereby stopped, although the machine will still continue to run.

For nice adjustment of the position on the rod E of the contact-finger, and in order that such adjustment may be clearly indicated to the eye and the position of the tool as to depth in the work at all times shown, a dial-plate E⁷ is provided, which may preferably

be marked off into spaces indicating a thousandth of an inch. A pointer E⁸, actuated by a cogged segment E⁹, is carried on a lever E¹⁰, the short arm of which is connected to the stop-arm E³, mounted on the rod E. By this arrangement the depth of the tool will be indicated on the dial and the setting of the stop-motion to work at the required depth is facilitated.

It sometimes happens or may happen that the speed of rotation given to the milling-tool is not great enough, even when the highest speed is given of which the driving-shaft C¹³ is capable. Of course it will be understood that this condition is one which is only likely to exist when a very small milling-tool is employed, because, as is well known, the smaller the diameter of the cutting-tool the higher should be its speed of rotation within proper limits. A very small tool for operating in corners and narrow cavities should of course revolve at a very high speed to do good work. In this machine such a high speed of rotation of the milling-tool may be very easily attained without interfering with the feed and driving operation as follows: On the lower end of pinion D⁷, which under ordinary circumstances is the gearing which drives the tool-carrying spindle D', is fixed a small band-wheel F, grooved to receive a cord belt, and provision is made for slipping on its shaft the pinion D⁸, out of mesh with its driving gear or pulley. At each side of the machine are guide-pulleys F' F', and at a convenient point below is a large grooved band-wheel F², mounted on a shaft F³ and provided with driving-pulleys F⁴. An endless cord (not shown in the drawings) passes around the small band-wheel F, over the guide-pulleys F' F', and around the large band-wheel F². Power applied to any one of the band-wheels F⁴ will of course transmit the motion of the band-wheel F² through the cord to the band-wheel F, and consequently to the spindle D' and the tool D, and this speed may be as high as desired, as the movement is independent of the mechanism which operates the other parts of the machine and there is no necessary relation required between the rotary motion of the tool and said other motion of the machine.

The work-holder shaft B, together with the pattern D¹⁰, connected thereto, may be easily and quickly removed from the machine, and without interference with any of its gearing, by turning the hand-wheel B¹⁰, which pushes said shaft and the pattern-holder endwise out of its bearings toward the front of the machine, leaving the rest of the machine intact and still in condition to operate. The purpose of thus making this shaft removable and replaceable is in order that a plane-surface work-holder or chuck may be easily substituted for the oscillating one for cylindric surfaces, and when the machine is to be used for sinking dies upon plane surfaces said shaft B or cylindric work-holder is thus

removed entirely from the machine, leaving the way clear for use of the plane-surface work-holder or chuck, which is located on the frame of the machine immediately beneath.

5 This plane-surface work-holder or chuck, which may be permanently connected with the machine and is so shown in the drawings, will now be described.

The chuck is organized to give to the work 10 in a horizontal plane the following movements: first, a movement in a right line across the machine from side to side at a speed which may be adjusted; second, a movement transverse to and at any required 15 angle to the first movement; third, a circular movement, the center of which may be adjusted to any desired point within the limits of the other movements of the chuck, and, fourth, compounds of any two or more of the 20 foregoing movements.

The chuck as a whole, aside from the devices which impart the movements, consists of four principal parts: first, a movable bracket or support from the frame of the ma-

25 chine by means of which the chuck as a whole may be raised and lowered vertically to suit the exigencies of the work and to bring it into closer proximity to the cutting-tool; secondly, a lower sliding bed-plate mounted on this 30 bracket and adapted to move in a right line across the machine; third, a pivoted bed-plate pivoted to turn upon the lower sliding bed-plate; fourth, an upper sliding bed-plate ar- 35 ranged to slide in ways upon the pivoted bed-plate.

The means for giving movement to various parts consists of a principal shaft lying in the direction of movement of the lower bed-plate and carrying a splined bevel-pinion and a 40 screw and receiving its rotary movement from the gearing of the machine, as will presently be described. The screw on this shaft is the means employed for giving the right-line movement to the lower bed-plate, and the 45 splined pinion sliding on the shaft meshing into a circular rack toothed on both sides, and which may revolve loose in or be locked to the pivoted bed-plate, is the means for communicating motion of a rotary character 50 to the pivoted bed-plate when locked thereto or when loose therein when transmitting power to the second screw-shaft to move the upper bed-plate.

Having thus stated generally the characteristics of the chuck as a whole, minuter description of the same will now be given by the aid of the drawings.

G is the bracket or carriage, mounted to slide in ways G' on the frame of the machine 60 and capable of vertical adjustment by means of the screw G² turning in the nut G³, the latter supported from the frame of the machine. This screw carries at its upper end a bevel-pinion G⁴, which engages a bevel-pinion 65 G⁵ on the horizontal shaft G⁶, the outer end of which is squared to receive a crank-handle, so that the screw may be easily turned by the

operator in raising or lowering said bracket from a position in front of the machine. The lower bed-plate of the chuck is shown at H 70 and is constructed to slide in a right line transversely on the bracket G. The principal shaft is shown at H' lying transversely of the machine, mounted in bearings on the bracket G, and carrying the feed-screw H², the 75 threads of which are cut on a sleeve, to which sleeve is attached a hand-wheel H³. A friction-clutch H⁴ connects the screw-sleeve firmly to the shaft when the feed is desired to be automatic; but when this friction-clutch 80 H⁴ is released this screw-sleeve may be turned by hand—as, for example, in setting the work. The screw works in a nut H⁵, carried by the bed-plate H, so that the rotation of said screw will move said bed-plate on its ways trans- 85 versely across the bracket G in one or the other direction, according to the direction of rotation of said screw. Splined to the shaft H' and carried in bearings on the bed-plate H is the bevel-pinion H⁶.

H⁷ is the pivoted bed-plate, held down to the bed-plate H by the pivotal bolt H⁸, having the enlarged head H⁹ setting under a portion of said bed-plate H. Bolts H¹⁰, passing down through the pivoted bed-plate H⁷ 95 and having heads which engage the circular groove H¹¹ in said bed-plate H, afford means for locking said pivoted bed-plate to said bed-plate H whenever desired, so that said pivoted bed-plate may be left free to rotate on its 100 pivot or locked fast in any position. Mounted loosely in the pivoted bed-plate H⁷ is the circular rack H¹², having cogs on its lower surface which engage the cogs of the bevel-pinion H⁶, and having cogs on its upper surface 105 which engage the bevel-pinion H¹³, this latter pinion being mounted loosely on the shaft H¹⁴, which carries the screw H¹⁵, to which shaft it may be connected by means of a friction-clutch H¹⁶, operated by the screw-nut H¹⁷. Said friction-clutch is provided with a hand-wheel H¹⁸, so that the screw H¹⁵ may be operated independently of the pinion H¹³ when desired. Mounted on the pivoted bed-plate H⁷ is the upper sliding bed-plate H¹⁹, 110 connected to the screw H¹⁵ by a nut H²⁰. On the surface of this upper sliding bed-plate H¹⁹ is mounted the movable jaw H²¹, which may be set forward by the set-screws H²² and locked in position by a bolt H²³, the latter 115 working through slots in the bed-plate. Opposing this movable jaw is a stationary jaw H²⁴, and between these two jaws the work is to be held. On this stationary jaw H²⁴ is mounted the guide, pattern H²⁵ in position to 120 be engaged by the guide-finger D¹⁰, above described, carried upon the head which carries the milling-tool, and which guide-finger determines automatically the depth to which the milling-tool shall cut in the traverse of 125 the work, when said cuts are not to be in the horizontal plane but of varying depth to suit some particular configuration.

On the shaft H' is the bevel-pinion J, mesh-

ing with the bevel-pinion J' , carried on the shaft J^2 , on the other end of which is the bevel-pinion J^3 , meshing with the bevel-pinion J^4 , splined to the shaft J^5 . The gearing J' 5 $J^3 J^4$ is all carried on the bracket G and moves with said bracket, while the shaft J^5 is mounted on the frame of the machine. Hence the necessity for splining the pinion J^4 to said shaft in order that the chuck-carrying 10 bracket may be moved or adjusted up and down. On the upper end of the shaft J^5 is a bevel-pinion J^6 , meshing with the bevel-pinion J^7 on the shaft J^8 . On the shaft J^8 is mounted the cog-wheel J^9 , which engages 15 with one of a series of graded gears J^{10} . These graded gears J^{10} are mounted on the same shaft G^{20} which carries the graded gears G^{21} , hereinbefore described, and consequently receive motion by the intermediate gearing 20 above described of the same character and capable of the same regulation as that imparted to the work-holder shaft B when the latter is in use—that is to say, the shaft H' which operates to move the chuck is by this 25 means caused to rotate for a certain specified time and regulable amount first in one direction and then in the other, causing the work to traverse beneath the milling-tool and in a horizontal plane first in one direction be- 30 neath said tool and then in the reverse direction, whatever may be the line of its path, and of course it will be understood that the extent of this traverse may be regulated by the adjustment of the reversing-gear above 35 described in relation to said work-holder shaft B and in the same manner.

The operation of the chuck is as follows: The work being clamped in the jaws on the upper bed-plate and the whole chuck being 40 raised into proper position for the milling-tool to engage it and the extent of traverse required having been determined upon and the gearing for feeding and reversing set the machine is started and the required cut made. 45 When it is desired to make a straight cut in a direction across the machine, all of the parts of the chuck may be locked together and the feed of the upper screw thrown off. The chuck will traverse the work to and fro in a 50 right line across the machine. However, if for any reason the line of cut cannot be made to coincide with the axis of the main feed-screw then the clutch of this main feed-screw may be thrown off and the clutch of the upper 55 feed-screw set up to bring said upper feed-screw into operation and the upper bed-plate turned on the pivot until the upper screw will be in line with the required movement. The pivoted bed-plate is then locked fast to the 60 lower bed-plate and the rotary movement of the shaft H' will be transmitted through the circular rack to the upper screw, producing a rectilinear traverse in the angular direction desired. Should it be desired to give the 65 work a circular motion, the main screw being unclutched as well as the upper screw and the rectilinear feed being thus thrown off, the

pivoted bed-plate is released, so that it shall become free to turn, and at the same time the circular rack H^{12} is locked fast by means of a 70 set-screw K , (not before mentioned,) so that it cannot turn without also revolving said pivoted bed-plate, and also revolving the upper bed-plate and the work carried thereby. The work will now have a horizontal rotary 75 movement on its center coincident to the axis of its pivot, and this center may of course be adjusted to any required position in a horizontal plane by means of working with the hand-wheels one or both of the feed-screws; 80 or, if desired, both of the feed-screws may be kept in gear and the pivoted bed-plate held rigid, when the movement of the work will be of course a compound or resultant of the two motions, or either one of these two motions 85 may be compounded with the circular motion with a corresponding resultant. This makes the chuck most universal in its action, so far as cutting in a horizontal plane is concerned, and makes it peculiarly adapted to be operated 90 in conjunction with the same milling-cutter, guiding and regulating apparatus adapted to be used with the oscillating work-holder and without in any manner interfering with said mechanism, so that either the horizontal 95 plane chuck or the oscillating work-holder may be substituted in the machine, one for the other at will, and this together makes the whole machine one most admirably adapted to take its place in the shop as a universal die-sinking machine capable of working either 100 upon plane surfaces or cylindrical surfaces automatically.

The machine is also adapted for and can be used for drilling. To do this work, a continuous feed is employed instead of the intermittent feed heretofore described. To produce the continuous feed, the thumb-nut X on the shaft D^{12} is tightened on the miter-gear X' , which meshes with a miter-gear X^2 on shaft C^{20} , thus imparting a continuous feed or downward movement to the shaft D^{12} and the sliding carriage D^{50} , which carries the journal-box of the mill-spindle D' . To effect this, the adjusting-lugs C^3 are also removed. 115

I claim—

1. In a die-sinking mechanism the combination of a continuously-rotating milling-tool holder, means for rotating the same, means for feeding said holder down at stated intervals at each traverse of the work, regulable means for reversing the direction of motion of the gearing which moves the work under the tool at each traverse of the work, together with means for connecting a removable oscillatory work-holder to said reversible driving-gearing, and a horizontally-moving to-and-fro traversing chuck and means for connecting the mechanism of said chuck to said reversible driving-gearing, substantially as 125 specified.

2. The universal die-sinking machine adapted to work on either plane or cylindrical surfaces, in which is combined a main driving-

- shaft continuously rotating in one direction, an automatic shifting clutch and driving-gearing for changing the direction of the motion received from said driving-shaft, an adjustable automatic clutch-shifting device, a removable, oscillatory reversibly-traversing work-holder shaft, adapted to be connected to said reversible gearing, means for so connecting the same, and a horizontally-moving, to-and-fro traversing chuck also connected to said reversible driving-gear, substantially as specified.
3. The combination with the oscillatory reversibly-traversing removable work-holder shaft, of the reversing-wheel carrying the adjustable clutch-actuating stops and mounted on a sleeve fitted to receive the end of said work-holder shaft and oscillate the same, substantially as specified.
4. The combination with the main driving-shaft, of two loose opposing beveled pinions mounted thereon, the sliding friction-clutch interposed between said pinions, the clutch-actuating rod working in a cavity in the shaft and connected to said clutch, the lever connected to said rod, said lever being operated to move in opposite directions by stop-arms on a reversing-wheel, said reversing-wheel and its adjustable stop-arms, the bevel-gear meshing with the two pinions, its shaft, the worm carried thereby, the screw-gear on an intermediate shaft, and the series of graded gears to mesh therewith on the reversing-wheel, the whole constituting a mechanism for automatically converting the continuous rotation of the driving-shaft to an oscillatory movement, substantially as specified.
5. In a milling-machine, the work-holder shaft splined to the driving-gear so that it shall be free to move endwise, a spring for holding said shaft in one direction, a pattern mounted on a box in which said shaft oscillates, a feeling-finger mounted on and oscillating with said shaft, and means for moving the box bodily in and out carrying the shaft and its attachments therewith, substantially as specified.
6. In a milling-machine, the work-holder shaft splined to the driving-gear so that it shall be free to move endwise, a spring for holding said shaft in one direction, a pattern mounted on a box in which said shaft oscillates, a feeling-finger mounted on and oscillating with said shaft, and means for moving the box bodily in and out carrying the shaft and its attachments therewith, said means consisting of a rack on the box and a pinion on the frame of the machine, substantially as specified.
7. The combination in a die-sinking machine of a milling-tool holder consisting of a shaft splined to its driving-gear and mounted in a sliding head, held down by a spring interposed between said head and an adjustable sliding carriage, and means for feeding said carriage down toward the work, substantially as specified.

8. The combination in a die-sinking machine of a milling-tool holder consisting of a shaft splined to its driving-gear and mounted in a sliding head, held down by a spring interposed between said head and an adjustable sliding carriage, and means for feeding said carriage down toward the work, said means consisting of a pinion and shaft mounted on the frame of the machine and a rack affixed to the carriage, substantially as specified.

9. The combination with the sliding and spring-depressed and adjustable tool-carrying head, provided with a downwardly-extending feeling-finger, of an oscillating work-holder shaft carrying the pattern for guiding the tool in its up and down movements for contour, and said pattern mounted on the shaft and moved therewith, substantially as specified.

10. The combination of the automatically-operated reversing clutch-lever for reversing the driving-gear, of a connecting-rod connected to said lever and carrying a fork at its other end, resting on a rock-shaft carrying two ratchets geared to a counter-shaft which in turn is geared to the head carrying the milling-tool for feeding said milling-tool down to the work, and a stop-rod carrying an adjustable stop-arm arranged to come in contact with a lifting-lever connected to said before-mentioned connecting-rod for lifting said connecting-rod out of contact with the rock-shaft, all combined and arranged substantially as specified and constituting an automatic feed mechanism for feeding the milling-tool down a specified distance at each reverse of the driving-gear and for stopping said feed automatically when a certain depth has been reached, substantially as set forth.

11. The chuck comprising in combination the supporting bracket or base, the lower bed-plate fitted to the slide thereon, a screw-shaft carrying a screw for giving motion to said lower bed-plate and carrying a pinion for giving motion to a circular rack, said circular rack having teeth on both faces, a second pinion meshing in said circular rack and mounted on a screw-shaft for giving motion to an upper bed-plate, said upper bed-plate, and means thereon for holding work, substantially as specified.

12. The means for imparting motion from one screw-shaft to another screw-shaft in a chuck having two sliding bed-plates consisting in the combination of the two bed-plates, the bevel-pinions mounted on the two screw-shafts, said two screw-shafts, and an interposed circular rack having teeth on both faces, substantially as specified.

13. The universal horizontal movement chuck, consisting of a lower bed-plate mounted to be moved in slideways on its support or base by means of a driving-screw, an intermediate pivoted bed-plate adapted to rotate on said lower bed-plate, and an upper bed-plate adapted to slide on said pivoted intermediate and be moved thereon by means of

a screw-shaft, said two screw-shafts, a bevel-pinion on each of said shafts and a circular rack having teeth on both faces and meshing with said pinion, together with means for locking together the lower bed-plate and the pivoted intermediate, the upper bed-plate and the pivoted intermediate, and the circular rack and the pivoted intermediate, substantially as specified.

10 14. The combination with the screw-actu-

ated lower bed-plate, of the bed-plate pivoted thereto, the circular rack, and means for locking said rack, the screw-shaft for driving the lower bed-plate and the pinion thereon meshing with the circular rack, substantially as 15 specified.
